Primary Examiner — Philip S Hyder*Assistant Examiner* — Darlington Ly(74) *Attorney, Agent, or Firm* — Burns & Levinson LLP; Joseph M. Maraia**CLAIM**

We claim the ornamental design for a three-wheeled vehicle, as shown and described.

DESCRIPTION

FIG. 1 is a front and left side perspective view of the three-wheeled vehicle showing our new design;

FIG. 2 is a front elevation view thereof;

FIG. 3 is a left side elevation view thereof;

FIG. 4 is a right side elevation view thereof;

FIG. 5 is a rear elevation view thereof;

FIG. 6 is a rear and right side perspective view thereof; and, FIG. 7 is a top plan view thereof.

The broken lines in the drawings illustrate portions of the three-wheeled vehicle that forms no part of the claimed design.
